US00D531371S

(12) **United States Design Patent** (10) **Patent No.:** **US D531,371 S**
Barquin Santillan et al. (45) **Date of Patent:** **** Oct. 31, 2006**

(54) **IRON**

(75) Inventors: **Francisco Javier Barquin Santillan**,
 Pembroke Pines, FL (US); **Luis Raul**
Moysen Mason, Queretaro (MX)

(73) Assignee: **Aplica Consumer Products, Inc.**,
 Miramar, FL (US)

(**) Term: **14 Years**

(21) Appl. No.: **29/243,357**

(22) Filed: **Nov. 22, 2005**

(51) **LOC (8) Cl.** **07-05**

(52) **U.S. Cl.** **D32/70**

(58) **Field of Classification Search** D32/68-72;
 38/69, 74-75, 77.1-77.9, 90-97; 219/245-248
 See application file for complete search history.

Primary Examiner—Pamela J. Burgess

(74) *Attorney, Agent, or Firm*—Baker Botts L.L.P.

(57) **CLAIM**

We claim the ornamental design for an iron, as shown and described.

DESCRIPTION

FIG. 1 is a perspective view taken from the front, top, and right side of an iron showing my new design;

FIG. 2 is a left side elevation view thereof;

FIG. 3 is a front elevation view thereof;

FIG. 4 is a right side elevation view thereof;

FIG. 5 is a rear plan view thereof;

FIG. 6 is a top elevation view thereof; and,

FIG. 7 is a bottom plan view thereof.

1 Claim, 4 Drawing Sheets
